UNITED STATES PATENT OFFICE.

GRAFTON E. LUCE, OF NEW LONDON, OHIO, ASSIGNOR TO LANCASTER IRON WORKS, INC., OF LANCASTER, PENNSYLVANIA, A CORPORATION OF PENNSYLVANIA.

BRICK-SETTING MACHINE

Application filed August 26, 1927. Serial No. 215,628.

This invention pertains to a brick setting machine of that type adapted to be elevated by crane for engaging and elevating a stack of brick which have been set up or hacked in predetermined relation. It is generally employed in handling bricks during their manufacture in transferring the stack of brick from the car to the kiln or from the kiln to any place of deposit.

10 This type of setter generally embodies a series of fingers adapted to be inserted in the spaces between the brick of the lower course of the brick unit, the upper courses of the unit being supported by the fingers and basic 15 course being grasped by grasping members carried by the fingers and operable for grasping by the weight of the upper courses.

Another feature of the invention resides in the provision of a compensating mechanism, 20 in the form of a manually operated lever for accommodating the gripping action of the lower course of brick to any varying amount of brick supported by the setter. Inasmuch as the gripping action on the lower course of 25 the brick is caused by the weight of the superimposed brick, in event a lesser number of brick is desired to be carried the gripping action on the lower course will be lessened. By means of the compensating mechanism, the 30 same gripping pressure on the lower course is obtained regardless of the number of superimposed brick in the stack. This permits the setter to operate properly upon a stack having varying numbers of courses. With the 35 previous construction of setters it is common practice to provide an additional man to ride the setter and supply by his own weight the force needed to grasp the lower course when a small number of brick are to 40 be handled.

The entire finger and grasping mechanism is included in the height of one brick instead of two as has heretofore been customary. With the previous construction of grasping plates, 45 it has been necessary to set the two bottom courses of brick exactly alike with the brick one above the other with their axes in the same direction. This results in an unstable foundation for the brick unit. With the finger construction herein disclosed it is possible to set the second course with the courses of brick arranged at right angles, thus making 50 this part of the unit as stable as any other part. Another advantage of this construction is that the lifting fingers may be inserted

in any course of the unit and therefore as many courses as desired may be removed from the unit at one time.

While each of the lifting fingers are shown herein as embodying a plurality of grasping blocks, it is not necessary that each of them be provided therewith, but the grasping blocks may be employed on every other finger so that only one side of the brick will be 60 grasped thereby and clamped against the 65 finger on the other side thereof.

The full nature of the invention will be understood from the accompanying drawings and the following description and 70 claims:

Fig. 1 is a side elevation. Fig. 2 is a rear elevation. Fig. 3 is a section taken on the line 3—3 of Fig. 2. Fig. 4 is a side elevation of a portion of a finger with parts thereof broken away. Fig. 5 is a plan view looking 75 down on the finger as shown in Fig. 4. Fig. 6 is a section taken on a line 6—6 of Fig. 4.

In the drawings there is shown a brick setter having a supporting platform 10 suspended from a suitable overhead crane or 80 the like thru the hook and eyes 11. Movably connected to the platform 10 thru the medium of the bolts 12 there is an annular turn table support 13 upon which there is rotatably mounted a turn table 14. Intermediate the platform 10 and the upper ends of the bolts 12 there are compression springs 15 which normally maintain the table 10 and support 13 together by their spring tension, compensating for the normal weight of the 85 unloaded setter. Thus when no load is on the setter, said support is held adjacent to table by the springs 15. Centrally positioned with respect to the turn table 14 there is an actuating rod 16 held against vertically 90 sliding movement with respect to table 10 by the collars 17, but permitted to rotate therein. The lower end of the rod 16 is pivotally connected with one end of the link 20, the other end of the link being pivotally connected to the upper frame portion secured to the turn table 14. Pivotally secured intermediate the ends of link 20 there is a connecting rod 22 which extends downwardly having its lower end suitably connected with the 95 end of the arm 23. The arm 23 is keyed to the shaft 24 which is rotatably supported in the bearing brackets 25 secured in the depending frame members 26.

Keyed to the shaft 24 which extends 110

throughout the entire width of the setter, and spaced at intervals there along, there are a plurality of arms 27 having heads 28 at their lower ends through which a rod 29 extends. 5 Mounted on said rod adjacent the head 28 there is a head 30 formed on the lever 31 which extends downwardly and is provided with a notch 32 in its lower end adapted to embrace the pin 33 secured in the rear end 10 of the actuating bar 34. The arm 31 is rotatably mounted so as to fulcrum about the shaft 35 which also extends throughout the entire width of the setter. Positioned intermediate the head 28 on the lever 27, and 15 the inner end of the rod 29 there is a compression spring 36 which normally maintains the heads 28 and 30 in engagement.

From the above described structure, it will be apparent that without a load the setter 20 will be suspended from the platform 10 without any gap between said platform and turn table. It will also be capable of rotation about the actuating rod 16 as the center. However, when a load of brick is placed upon 25 the setter, or lifted thereby, the tension of the springs 15 will be overcome so that the setter will drop down slightly from the table 10. This movement will cause the link 20 to be pulled upwardly by the actuating rod 16 30 which will impart a partial clockwise rotation to the shaft 24 drawing the heads 28 and 30 inwardly toward the setter and forcing the bars 34 rearwardly away therefrom as indicated by the arrows in Fig. 1. This rearward action of the bars 34 will cause the gripping action of the lower course of brick 35 which will be hereinafter more fully described.

In order to compensate for varying weights 40 supported by the setter by reason of variations in the number of courses of brick carried thereby, there is provided a compensating lever 37 which is normally held in non-effective position by the clip 38, said lever being formed to pass about the shaft 24 and extend downwardly to the shaft 39 to which it is keyed, said shaft running the full width of the setter. Said shaft is supported in a suitable bearing 40 mounted on the frame support 26. At each end of the shaft 39 and at the center thereof there is keyed a gear 41 which is adapted to mesh with the gear 42. The shaft 35 is eccentrically carried by the gear 42, which is rotatably supported by the 45 bearing block 43. By means of this arrangement, upon pulling the lever rearwardly the gear 41 is turned in the direction of the arrow which causes the rotation of the gear 42 whereupon the shaft 35 is moved rearwardly 50 causing a rearward positioning of the bars 34.

Thus, the operator upon desiring to set a smaller and lighter stack of brick may reposition the bars 34 so as to partially engage and grip the brick before the load further actuates them. Thus the lighter load is as-

sisted by the auxiliary gripping action due to the operation of the compensating lever.

As shown in Fig. 1 by dotted lines, there is a stack of brick 45 comprising a lower course 46 and a second course 47 mounted 70 therein. The lower course of brick are formed in rows spaced from each other to permit the lifting fingers 48 to be inserted therebetween. Said fingers are of less width than the height of the course but are enlarged at 75 the rear as indicated at 49 and rigidly supported by the angle iron frame 50 so as to be rigid and sufficiently strong to support the entire stack of brick.

The actuating bars 34 are slidably mounted 80 within the fingers 48 and extend longitudinally thereof. The fingers 48 are provided with a plurality of openings indicated at 49 which are so spaced longitudinally thereof as to provide two of said openings within the 85 length of each brick. The bars 34 have openings registering with the openings 51 in which the grasping blocks 52 are inserted and slide laterally upon the key way blocks 53. Each of the blocks 52 are provided with upper and lower flanges 54 which taper longitudinally so as to provide longitudinally extending cam faces as best shown in Fig. 5. The bars 34 are provided with co-acting flanges having cam faces 55 on each side of 90 the slot therein embracing the blocks 52. The upper and lower cam faces of each of the blocks are reversed and likewise the co-acting cam faces of the bars 34. By means of this arrangement, when the bars 34 are caused to slide rearwardly with respect to the fingers 48, the engagement of the cam faces between the blocks and the bars cause the blocks to be forced laterally into grasping position. When the bars are moved in the opposite direction 100 the reversed cam faces on the opposite side thereof cause the blocks to be pulled inwardly out of grasping position. Thus, there is a positive grasping and releasing action of the blocks depending upon the direction of movement of the bars 34. For suitably engaging the brick and assisting in the grasping action, the ends of the blocks are provided with outwardly extending knife edges 56, as shown in 105 Fig. 5. As before stated, the openings in the fingers are spaced apart, two to each length of brick, one block acting upon one side of the arm and the other on the opposite side so as to engage and grip the brick on each side of the finger.

It will be borne in mind that the principal strain in the lifting of the stack is borne by the rigidity of the fingers 48, the grasping blocks being only employed for grasping and raising the lower course of brick. Thus, there is no substantial strain imposed on the grasping block other than that exerted by the weight of its individual brick.

An important feature of the invention resides in the formation of the grasping face of 130

the block 52 for adapting it to grasping bricks of varying widths within normal limits. The knife edges 56 formed on each end of the block will penetrate the brick slightly 5 for grasping it, the depth of the penetration depending upon the width of the brick. By reason of the recessed intermediate portion, there is sufficient space to allow for variations in thickness without damaging the surface 10 of the brick.

The invention claimed is:

1. A brick setting machine including a supporting member, a frame suspended therefrom, means secured to said frame for supporting a stack of brick, means for grasping the lower course thereof and means operable by the relative movement between said supporting member and frame for actuating said grasping means. 15
2. A brick setting machine including a supporting member, a frame suspended therefrom, means secured to said frame for supporting a stack of brick, means for grasping the lower course thereof, means operable by 20 the relative movement between said supporting member and frame for actuating said grasping means, and a plurality of compression springs for preventing such relative movement by the weight of the frame and brick support, but permitting the same upon the weight of the brick supported thereby 25 overcoming the tension of said springs.
3. A brick setting machine comprising a suspended support, a frame supported thereby and having a plurality of brick supporting fingers, grasping members associated with said fingers, means for permitting relative movement between said support and frame and means operated by said relative movement for actuating said members. 30
4. A brick setting machine comprising a suspended support, a frame supported thereby and having a plurality of brick supporting fingers, grasping members associated with 35 said fingers, means for permitting relative movement between said support and frame, means operated by said relative movement for actuating said members, and means for permitting said relative movement only by the weight of the brick supported on said fingers. 40
5. A brick setting machine including a supporting member, a turn table frame supported thereby, a turn table rotatably mounted in said frame, a setter frame suspended 45 from said turn table and having a plurality of brick supporting fingers, grasping members on said fingers, and means connected with said supporting member and setter frame for operating said members actuated by the relative movement between said supporting member and frame upon a load of brick being supported thereby. 50
6. A brick setting machine comprising a supporting member, a turn table frame suspended 55 therefrom and movable relative
- thereto, a turn table rotatably supported by said turn table frame, a setter frame suspended therefrom having a plurality of brick lifting fingers, grasping members therein, a rod rotatably mounted on said supporting member and extending centrally of said turn table, and means connected to said rod and said members for actuating the latter upon the setter frame and supporting member being separated by the weight of the brick carried thereby. 70
7. A brick setting machine comprising a supporting member, a turn table frame suspended therefrom and movable relative thereto, a turn table rotatably supported by 75 said turn table frame, a setter frame suspended therefrom having a plurality of brick lifting fingers, grasping members therein, a rod rotatably mounted on said supporting member and extending centrally of said turn table, means connected to said rod and members for actuating the latter upon the setter frame and supporting member being separated by the weight of the brick carried thereby, and means for normally resisting the separation thereof by the weight of the setter. 80
8. A brick setting machine comprising an overhead support, a turn table frame suspended therefrom by a plurality of bolts slideable therein for permitting relative movement, a turn table rotatably mounted on said turn table frame, an actuating rod rotatably mounted in said supporting member and extending downwardly therefrom centrally of said turn table, a setter frame suspended from said turn table and having a plurality of brick supporting fingers, a plurality of grasping members on said fingers, a link pivotally connecting the lower end of said rod 85 to said turn table frame, means operably connecting said link with said members for actuating the same upon relative movement of the setter frame with respect to said supporting member, and compression springs 90 mounted on said bolts for resisting such relative movement thru the weight of the setter frame, but permitting the same and the actuation of said members upon a load of brick 95 supported thereby. 100
9. A brick setting machine including a supporting member, a setter frame, a plurality of bolts connecting said member and frame for permitting relative movement therebetween and a spring on each of said bolts for normally resisting the separation of said member and frame thru the weight of the latter, but permitting such relative movement thru the weight of a load of brick carried thereby. 110
10. A brick setting machine including a plurality of brick supporting fingers, brick grasping members associated therewith, means for actuating said members thru the weight of the brick supported by said fingers, 115
- 130

- and a manually actuated lever operatively connected with said members for compensating for the loss of grasping action upon a decreased load of brick being supported by said fingers.
11. A brick setting machine including a plurality of brick supporting fingers, brick grasping members associated therewith, means for actuating said members thru the weight of the brick supported by said fingers and means operatively connected with said members for compensating for the loss of grasping action upon a decreased load of brick being supported by said fingers.
12. A brick setting machine including a plurality of brick supporting fingers, a plurality of grasping members associated with said fingers, a lever fulcrumed on the setter and operatively connected with said members for forcing the same into grasping position, means controlled by the weight of the brick carried on the said fingers for actuating said lever, and means for varying the position of the fulcrum of said lever so as to compensate for a reduction in the weight of the supported brick.
13. A brick setting machine including a plurality of brick supporting fingers, a plurality of grasping members associated with said fingers, a lever fulcrumed on the setter and operatively connected with said members for forcing the same into clamping position, and an actuating lever operatively connected with said fulcrumed lever for varying the position thereof so as to compensate for variation in weight of the supported brick.
14. A brick setting machine including a plurality of brick supporting fingers, a plurality of grasping members associated with said fingers, an actuating lever, a shaft upon which said lever is fulcrumed, operating means for connecting said lever with said members, means for operating said lever actuated by the weight of the supported brick and means for varying the position of said fulcrum shaft for compensating for variations in the weight of the supported brick.
15. A brick setting machine including a plurality of brick supporting fingers, a plurality of grasping members associated with said fingers, an actuating lever, a shaft upon which said lever is fulcrumed, operating means for connecting said lever with said members, and a manually operated lever having an eccentric connection with said fulcrum shaft for varying the position and the corresponding movement of the fulcrumed arm and compensating for variation in weight of the supported brick.
16. A brick setting machine having a plurality of rigid brick supporting fingers, a plurality of grasping blocks mounted in said fingers so as to slide laterally thereof, cam faces formed on said blocks, actuating bars slidably longitudinal of said fingers and said bars embracing said blocks provided with oppositely disposed cam faces adapted to co-act with the cam faces of said blocks for moving the latter in and out of clamping position, and means for actuating said bars.
17. A brick setting machine including a frame having a plurality of rigid forward extending fingers for supporting a stack of brick, grasping members associated with said fingers, reciprocating bars slidable longitudinally of said fingers for actuating said members, a shaft mounted on said frame, means controlled by the weight of the supported brick for rotating said shaft, a plurality of arms keyed thereto, fulcrumed levers having one end engaged with said actuating bar, and a yielding connection between said arm and lever for causing said members to be actuated therethru.
18. A brick setting machine including a frame having a plurality of rigid forward extending fingers for supporting a stack of brick, grasping members associated with said fingers, reciprocating bars slidable longitudinally of said fingers for actuating said members, a shaft mounted on said frame, means controlled by the weight of the supported brick for rotating said shaft, a plurality of arms keyed thereto, fulcrumed levers having one end engaged with said actuating bar, yielding connections between said arms and levers for causing said members to be actuated therethru, and a manually controlled member for varying the position of the fulcrum of said levers to compensate for variations in weight of the supported brick.
19. A brick setting machine having a plurality of rigid brick supporting fingers, a plurality of grasping blocks mounted in said fingers, and means for actuating said grasping blocks, said blocks being provided with spaced projecting portions adapted to pierce the brick and extending therein to varying depths, depending upon the width thereof.

In witness whereof, I have hereunto affixed my signature.

GRAFTON E. LUCE.
